H. RUBIN.

ELECTRIC LIGHT FIXTURE.

APPLICATION FILED AUG. 31, 1917.

Patented Aug. 27, 1918.

UNITED STATES PATENT OFFICE.

HARRY RUBIN, OF BALTIMORE, MARYLAND.

ELECTRIC-LIGHT FIXTURE.

1,276,966.

Specification of Letters Patent. Patented Aug. 27, 1918.

Application filed August 31, 1917. Serial No. 189,111.

To all whom it may concern:

Be it known that I, HARRY RUBIN, a citizen of the United States, residing at Baltimore, in the State of Maryland, have invented certain new and useful Improvements in Electric-Light Fixtures, of which the following is a specification.

My invention relates generally to electric lighting fixtures and particularly to that type of the same wherein a reflector and bowl constitute a two-piece electric lighting unit, this unit being associated with a combined socket cover or sheet and a support therefor, the support being capable of vertical adjustment to properly position the light-diffusing bowl, which is suspended therefrom, relatively to the height of the room in which the fixture is to be located.

My invention also consists of the parts and the constructions, arrangements and combinations of parts which I will hereinafter describe and claim.

In the accompanying drawings forming part of this specification and in which similar reference characters indicate like parts in the several views;

Figure 1 is a side elevation partially in section of a two-piece electric lighting unit embodying my invention, showing the parts in section.

Fig. 2 is an enlarged detail to be hereinafter referred to.

In carrying out my invention, I prefer to employ in association therewith the so-called buckle, 10, through which the conducting wires are usually led to the interior of the lamp-socket, said buckle having threaded openings at opposite ends, one of these openings being adapted to screw into engagement with a nipple or short pipe extension, 11, or like part fixed to or projecting from the ceiling or from an outlet box, not shown, or other fixture located in the ceiling.

The lower threaded opening of the buckle is designed for engagement with one end of a threaded pipe, 12, the lower end of this pipe having threaded engagement with an opening formed in the top of a support, A, and which support is shown as comprising an upper disk, 13, into the top of which the lower end of the pipe, 12, is threaded; and a lower disk, 14, appropriately spaced from the upper disk and the two disks being rigidly connected to form a cage-like structure by means of vertical rods, 15, spaced equidistant around the support, said rods

having their lower ends passing through openings in the lower disk, 14, and one or both ends of the rods being threaded to receive suitable securing nuts, 16. In the present instance, nuts, a, are shown on the lower ends of the rods and said rods may be internally threaded at their lower ends for the purpose of receiving the threaded shanks of small hooks, 17, which project vertically below the rods, and from which the light-diffusing bowl 18, may be appropriately suspended.

The means for suspending the bowl and which bowl may be of any desired design, may be varied without departing from the salient features of my invention, but I prefer as the suspending means small rods, 19, as such elements throw but little shadow on the ceiling when the light is burning, the lower ends of these rods being in turn connected to small hooks, 20, mounted in or on the sides of the bowl in a manner well known in this art.

Within the cage-like structure formed by the upper and lower disks, 13 and 14, and the annular series of rods, 15, is mounted a combined socket and socket-cover, or shell, the socket, 21, being of any approved type and being threaded to the lower end of the tube, 12, and the socket cover, or shell, being in the form of a porcelain or like non-conducting cylinder surrounding the socket and interposed between the same and the inner surfaces of the aforesaid rods, 15. This construction rigidly unites the socket and socket-cover, or shell, to the cage, since the upper end of the socket-structure bears against the upper disk, 13, and the lower end of the porcelain socket cover, or shell, seats directly against the upper beveled surface or seat, 14', of the lower disk, 14, said disk, 14, being open at the center so as to allow the plug of the usual electric light bulb to be entered therein and screwed into and out of engagement with the socket.

The structure described may be used in connection with canopies of different depth, as it is capable of vertical adjustment as a whole, since the cage and support may be screwed up and down on the threaded connection or pipe, 12, to thus raise and lower the support relatively to the canopy and accordingly raise or lower the light-diffusing bowl which is suspended from the lower end of said support, this adjustment being desirable to properly position the light rela-

tively to the height of the ceiling of the room in which the light is to be installed.

Associated with the light-diffusing bowl is a reflector, 22, of porcelain or other suitable material and which reflector I prefer to fashion in the form shown, namely, that said reflector shall have a greater diameter than the largest diameter of the bowl and that it shall have substantially a funnel-shaped portion being fashioned with concaved surfaces on the exterior and forming a reflecting surface whereby the beams of light from the inclosed lamp, within the bowl, will upon striking the curved surfaces be widely radiated into the room, or apartment and thus augment the lighting properties of the lamp.

From the foregoing it will be apparent that the improved device is simple and compact and may be cheaply furnished. Its parts may be readily assembled and they may be quickly detached for renewing and repair purposes. Also, the described arrangement is such that I am enabled to compensate for irregularities or differences in the shape and size of the reflector, or canopy.

The parts of the device are all rigidly secured together and maintained in proper position with respect to each other, and practically all the metal parts are inclosed and insulated by the socket-cover or shell, which is preferably made of porcelain or other non-corrosive and non-conducting material, and which cover or shell is itself inclosed by the funnel-shaped central projecting portion of the reflector or canopy.

Having thus described my invention what I claim as new and desire to secure by Letters Patent is:

40. 1. A lighting fixture comprising in combination a support, a canopy, a light-diffusing bowl, said canopy having a substantially funnel-shaped central portion with a concave reflecting surface, and a lamp-socket holder carried by the support adapted to support both the canopy and the light-diffusing bowl, said holder comprising upper and lower disks and intermediate spacing rods and a shell or casing inclosing a lamp-socket, the lower of said disks forming a support for the funnel-shaped portion of the canopy, and the shell or casing and the other disk forming a support for the lower disk.

55. 2. A lighting fixture comprising in combination a support, a canopy, a light-diffusing bowl, said canopy having a substantially funnel-shaped central portion with a concave reflecting surface, a lamp-socket holder carried by the support adapted to support both the canopy and the light-diffusing bowl, said holder comprising upper and lower disks and rods extending between the disks and holding them in spaced relation, and a shell or casing inclosing a lamp-socket, said upper disk being secured to said support

and said lower disk forming a seat and support for the central portion of the canopy and the shell or casing.

3. A lighting fixture comprising in combination a support, a canopy, a light-diffusing bowl, said canopy having a substantially funnel-shaped central portion with a concave reflecting surface, a lamp-socket holder carried by the support adapted to support both the canopy and the light-diffusing bowl, said holder comprising upper and lower plates and rods extending therebetween and holding the plates in spaced relation, and a shell or casing of insulating material between the rods and inclosing a lamp-socket, said upper plate being secured to said support and said lower plate forming a seat and support for the shell or casing and the canopy and having a central opening leading to the socket and adapted to admit the plug-end of a lamp.

4. A lighting fixture comprising in combination a support, a canopy, a light-diffusing bowl, said canopy having a substantially funnel-shaped central portion with a concave reflecting surface, a lamp-socket holder carried by the support adapted to support both the canopy and the light-diffusing bowl, said holder comprising upper and lower disks and intermediate spacing rods and a shell or casing inclosing a lamp-socket, one of said disks forming a support for the funnel-shaped portion of the canopy, and the shell or casing, and being adjustably secured to said support, said rods having threaded lower portions, suspending devices fitted to said threaded lower portions of the rods and to the light-diffusing bowl, and rods extending between said suspending devices.

5. A lighting fixture comprising in combination a support, a canopy, a light-diffusing bowl, said canopy having a substantially funnel-shaped central portion with a concave reflecting surface, a lamp-socket holder carried by the support adapted to support both the canopy and the light-diffusing bowl, said holder comprising upper and lower disks and intermediate spacing rods and a shell or casing inclosing a lamp-socket, one of said disks forming a support for the funnel-shaped portion of the canopy, and the shell or casing, and being secured to the support, said rods having internally threaded openings in their lower ends, hooks having threaded shanks engaging said openings, suspending devices on the light-diffusing bowl, and rods extending between said hooks and said suspending devices.

6. A lighting fixture comprising in combination a support, a canopy, a light-diffusing bowl, said canopy having a substantially funnel-shaped central portion with a concave reflecting surface, a lamp-socket holder carried by the support adapted to support both the canopy and the light-diffusing

bowl, said holder comprising upper and lower disks and rods extending between the disks and holding them in spaced relation, a shell or casing inclosing a lamp-socket, said 5 upper disk being secured to said support and adapted to support the funnel-shaped central portion of the canopy, and forming a seat and support for the lower end of the shell or casing, said rods having internally 10 and externally threaded lower ends, nuts engaging the externally-threaded ends of the rods, suspending devices having threaded shanks engaging the internally-threaded portions of the rods, suspending devices on 15 the light-diffusing bowl, and connections from the first-named to the second-named suspending devices.

7. A lighting fixture comprising in combination a threaded pipe forming a support, a combined socket and shell or casing, said 20 socket being secured to the support and said shell inclosing the socket and composed of insulating material, a cage-like structure inclosing the shell or casing and comprising an upper disk pierced to admit said pipe, a 25 lower disk having a central opening and forming a seat for the bottom of the shell or casing, spacing rods fixed to and extending between said disks, suspending devices on the lower ends of the rods, suspending de- 30 vices on the light-diffusing bowl, and connections between said suspending devices.

In testimony whereof I affix my signature.
HARRY RUBIN.
